UNITED STATES PATENT OFFICE.

VICTOR E. WASSERLEIN, OF NEW YORK, N. Y., ASSIGNOR TO WASSERLEIN, FROES COMPANY, INC., A CORPORATION OF NEW YORK.

CARBURETER NEEDLE-VALVE.

1,347,922.

Specification of Letters Patent.

Patented July 27, 1920.

Application filed October 2, 1917. Serial No. 194,410.

To all whom it may concern:

Be it known that I, VICTOR E. WASSERLEIN, a citizen of the United States, residing at New York, in the county of New York and State of New York, have invented certain new and useful Improvements in Carbureter Needle-Valves, of which the following is a specification.

This invention relates to carbureters and 10 has more especial reference to improvements in fuel flow regulating valves.

The invention has for its principal object 15 to provide a needle valve for use in carbureters and like charge forming devices, whereby the flow of fuel therefrom can be minutely controlled by the operator in order that the leanness or richness of the charge may be properly adjusted to allow perfect functioning of the motor receiving the same.

20 It is the more specific object of the invention to provide a novelly constructed valve, the same being capable of allowing a great number of adjustments whereby to regulate the flow of combustible gas.

25 The improvements in the details and arrangement of parts will be apparent from an inspection of the accompanying drawings, in connection with the specific description hereinafter contained, and where- 30 in the preferred embodiment of the invention is disclosed for the purpose of imparting a full understanding of the same.

In the drawings:—

Figure 1 is a side elevation of the im- 35 proved valve in its extended or elongated position;

Fig. 2 is a vertical transverse section therethrough;

Fig. 3 is a side elevation of the valve in 40 its contracted position; and

Fig. 4 is a fragmentary vertical section through a carbureter showing the improved valve arranged in working position thereon.

Similar characters of reference refer to 45 similar parts throughout the several views of the drawings.

Having more particular reference to the drawings, 1 represents the needle of the valve, the lower extremity of which is tapered as at 2 for an obvious purpose while the remaining end is screw threaded and is adapted for engagement with the casing of the carbureter *c*. In this connection, it is to be understood that the tapered portion 2 50 of the needle 1 is arranged in proximity of

the fuel outlet port of the carbureter, the purpose of which will be subsequently apparent.

A helix 3 is arranged about the needle 1 and has the lower portion or inner convolution of the same secured to the needle 1 at a point in proximity of the tapered portion 2, while the upper or outer convolution of the helix is secured to a disk or similar element 4, this element being rotatably mounted upon the needle 1 and provided with a spiral collar 5 having a spiral gear 6 meshing therewith and carried on the adjacent end of an operating shaft, which shaft is mounted in suitable bearings (not shown) 60 in the carbureter *c* and has its remaining end (not shown) extended to a point beyond the same whereby to facilitate rotation thereof. Inasmuch as the means for rotating the disk and the helix 3 may be varied 65 in design and construction, I do not intend to confine myself to any one embodiment but may vary the same, such as conditions or preference may dictate. The helix 3 may be and preferably is formed of flattened 70 spring metal, the tendency of which is to return to a normal position subsequent to elongation or contraction. In this connection it is to be also understood that the helix 75 3 is arranged at a point in proximity of the 80 fuel outlet port of the carbureter.

When using the improved needle valve in a carbureter such as indicated by the reference character *c*, the operating means therefor is rotated in a direction to cause elongation or contraction of the helix 3. Obviously by contracting the helix 3, the relative positioning of the same and the fuel outlet port of the carbureter will be so adjusted as to decrease the flow of fuel. How- 90 ever, by rotating the operating means in a direction to cause elongation of the helix the opening between the port and the helix will be increased, thus permitting a greater flow of fuel and as a consequence, a richer 95 charge. Due to the inherent resiliency of the helix 3 it will be readily understood that the same will be caused to instantly return to its normal position when released. Hence, adjustment of the same is such as to 100 cause the rapid response of the carbureter in the forming of the desired combustible charge adapted for introduction into the cylinders of the motor receiving the same.

Attention is directed to the fact that the 110

needle 1 is fixedly mounted upon a suitable support and has no movement with relation to the fuel outlet port of the carburetor; the helix 3 being the only movable element 5 and this being operated upon rotation of the means engaged with the outer or free convolution of the said helix.

Manifestly, the construction shown is capable of considerable modification and 10 such modification as is within the scope of my claims, I consider within the spirit of my invention.

I claim:

1. A valve comprising a fixedly mounted 15 pin, and a longitudinally adjustable expandible and contractile body arranged about said pin.
2. A valve comprising a pin, and a helix arranged about said pin and longitudinally 20 adjustable with respect thereto for regulating the operation of said valve.
3. A valve comprising a pin, a helix arranged about said pin having the inner convolution thereof secured to one end of said 25 pin, and said helix being longitudinally adjustable with respect to said pin for regulating the operation of said valve.
4. A valve comprising a pin, a resilient helix arranged about said pin and longitudinally 30 adjustable with respect thereto for regulating the operation of said valve,

the inner convolution of the helix being secured to the pin in proximity of one end thereof.

5. A valve including a pin, and a longitudinally adjustable spring helix arranged about said pin and connected thereto at one end, said helix being adjustable to permit variance of its length and diameter.

6. A valve including a fixedly mounted 40 pin in proximity to the valve seat and having a tapered end, a disk mounted adjacent the end opposite the tapered end, a helix of flattened material the inner convolutions of which is secured to the pin and means for 45 longitudinally moving said helix on the pin for regulating said valve.

7. A valve including a fixedly mounted pin in proximity to the valve seat and having a tapered end, a disk mounted adjacent 50 the end opposite the tapered end, a helix arranged about the pin and engaging the disk, the inner convolution of the helix being secured to the pin, the convolutions of said helix adapted for longitudinal adjustment with respect to said pin to creep 55 downwardly upon the tapered end and means for longitudinally adjusting said helix for the purpose described.

In testimony whereof I affix my signature 60 hereto.

VICTOR E. WASSERLEIN.
